UNITED STATES PATENT OFFICE.

SWITS CONDÉ, OF OSWEGO, NEW YORK.

DESIGN FOR KNIT SHIRTS.

SPECIFICATION forming part of Design No. 11,740, dated April 20, 1880.

Application filed March 26, 1880. Term of patent 7 years.

To all whom it may concern:

Be it known that I, SWITS CONDÉ, of Oswego, in the county of Oswego, in the State of New York, have invented new and useful Improvements in Design for Knit Shirts, of which the following, taken in connection with the accompanying drawing, is a full, clear, and exact description.

The accompanying drawing represents the body of an undershirt ornamented in accordance with my design.

a a denote straight and parallel continuous stripes, generally of one color, and arranged transverse or horizontally in relation to the garment. Intervening between the successive stripes *a a*, respectively, is a broken stripe, *b*, of a different color or colors than the continuous stripe *a*.

The breaks in the stripes *b b* are equidistant apart and of the same color as the continuous stripes which they thus connect. The breaks

in each succeeding stripe *b* are arranged midway over those of the preceding stripe.

What I claim is—

The design for knitted shirts, consisting of the parallel continuous stripes *a a* and the intervening broken stripes *b b*, of different colors, all arranged horizontally in relation to the garment, the breaks in the stripes *b* being of the same color as the continuous stripes, and each succeeding stripe *b* having its breaks respectively midway between those of the preceding stripe, substantially as shown.

In testimony whereof I have hereunto signed my name and affixed my seal in the presence of two attesting witnesses, at Oswego, in the county of Oswego and State of New York, this 10th day of January, 1880.

SWITS CONDÉ. [L. S.]
